UNITED STATES PATENT OFFICE.

JOHN F. GRACE, OF KEARNEY, NEW JERSEY, ASSIGNOR TO WORTHINGTON PUMP AND MACHINERY CORPORATION, A CORPORATION OF VIRGINIA.

CONDENSER.

Application filed November 6, 1919. Serial No. 336,026.

To all whom it may concern:

Be it known that I, JOHN F. GRACE, a citizen of the United States, residing at Kearney, county of Hudson, and State of New Jersey, have invented certain new and useful Improvements in Condensers, fully described and represented in the following specification and the accompanying drawings, forming a part of the same.

10 This invention relates to jet condensers, the especial object of the invention being to provide an improved jet condenser of low head, that is, small vertical dimensions, operating on ejector principles, which shall be 15 simple, cheap and convenient to manufacture.

A further object of the invention consists in the provision of means for maintaining a constant delivery to the condenser so that 20 the velocity of the water through the nozzle or nozzles shall be constant.

The invention further relates to the provision of means for separating air from the condensing water previous to its delivery to 25 the condensing nozzle or nozzles and means for the removal of the air.

For a full understanding of the invention a detailed description of a condenser embodying all the features of the invention 30 in their preferred form will now be given in connection with the accompanying drawing forming a part of this specification, and showing in central vertical section my improved condenser with its supply pump and turbine connected thereto, and the features 35 forming the invention then specifically pointed out in the claims.

Referring to the drawing,—

40 A designates a turbine supported by floor 10 and suitably connected below the floor to the condenser shell B provided at one side with cooling water inlet 11 connected by suitable connection 12 to the delivery of the cold water supply pump C, driven by 45 suitable means not shown. The condenser shell B is divided into a cold water supply chamber 13 and a steam inlet chamber 14 by an apron 15 having horizontal partition 16. An opening 17 in the bottom of the condenser shell B below the partition 16 is 50 closed by a plate 18 provided with suitable openings to receive a plurality of condensing nozzles 19, three of which nozzles are shown in the sectional view, which extend 55 into and preferably below the water level in

the collecting well 20 preferably formed in the foundation, as shown. Steam cones 21 pass through suitably arranged openings in the partition 16 and extend a short distance within the condensing nozzles 19 forming 60 therewith suitable annular passages 22 for the condensing water.

Condensing water delivered to the chamber 13 by the pump C passes to the annular passages 22 and thence downward, drawing 65 with it the steam from chamber 14 which is condensed and compressed therein and delivered to the collecting well 20 from which the water passes by overflow weir 23, which maintains a suitable water level within the 70 well 20, to the hot well 24.

In order to maintain a constant velocity of the water passing through the condensing tubes 19 and for this purpose a substantially constant head of water in the chamber 13, 75 I provide for supply flow velocity operated, automatic control of the supply pump driving means. In the construction shown I contract the inner end of the inlet 11 to form a nozzle 25 which delivers the water against 80 a flapper 26 pivoted at 27 to the condenser shell B and connected by rods 28, 29, to the lever 30 of a throttle valve 31 in the steam inlet pipe 32 of the pump driving means so that, as the velocity of flow through the 85 nozzle 25 falls or increases the corresponding lowering or raising of the flapper 26 will operate the valve 31 through its connections to correspondingly increase or decrease the supply of steam to the supply 90 pump driving means to maintain a constant water supply flow velocity through nozzle 25 whereby the water level in chamber 13 and the resulting velocity flow through condensing tubes 19 are maintained constant. 95 Preferably the rods 28, 29 are connected by a turn buckle 33 so that the relative position of the valve 31 and the flapper 26 may be regulated.

A further feature of my invention consists in providing means for separating air from the condensing water and for removal of same. To this end the apron 15 is extended downwardly about the nozzles 19 nearly to the bottom of the shell B thereby 100 forcing the water to flow downward to the bottom of the chamber 13, under the apron 15 and upward to the annular passages 22, so that the air separates and collects in the upper portion of the chamber 13 which is 105 110

connected by a passage 1 and one or more suitably formed pipes 2 to the space within one or more of the condensing nozzles 19 whereby the water in passing through the 5 nozzles also removes the air from the upper portion of the chamber 13. I preferably provide the passage 1 with a valve 3 operated by float 4 guided by any suitable means such as a pin 5 on its bottom sliding within a probe 10 jecton 6 on the condenser shell B to close pipe 1 in case the water rises above a proper level in chamber 13.

In small units I may use a single condensing nozzle, but in the larger units a plurality, for instance, six arranged in a circle about one central tube, as suggested in the drawing, is preferable, and this is an important feature in securing a low head condenser, as permitting the use of shorter nozzles, and providing thinner films of water which expose more surface for contact with the steam and thereby secure a more efficient condensation.

It is to be understood that the invention 25 is not limited to the detail construction shown and described, as many modifications may be made therein without departing from the invention as defined by the claims.

What is claimed is:

30 1. A jet condenser having a top steam chamber, a water supply chamber at one side of the steam chamber, a plurality of ejector-condensing nozzles having their open top ends directly below the steam chamber, a water 35 chamber surrounding the upper ends of the ejector nozzles, and an annular apron enclosing the water chamber about the ejector nozzles whereby the water passes from the water supply chamber beneath the annular edge of the apron to the water chamber.

40 2. A jet condenser consisting of a casing having horizontal partition 16 dividing the casing into an upper steam chamber and a lower condensing water chamber, a plurality of ejector condensing nozzles 19 having their upper ends within the water chamber and adjacent to said partition, annular apron 15 enclosing the water chamber about the condensing nozzles, and a water supply 45 from which water flows beneath the annular edge of the apron to the water chamber.

50 3. A jet condenser having a top steam in-

let chamber, a water supply chamber at one side of the steam chamber, a condensing nozzle having its open end directly below the steam chamber, a water chamber surrounding the upper end of the condensing nozzle, an annular apron enclosing the water chamber about the condensing nozzle thereby causing the water to pass from the water supply chamber to the water chamber beneath the annular edge of the apron and air to separate from the water before passing to the condensing nozzle, and a connection between the upper portion of the water supply chamber and the interior of the condensing nozzle for removal of the air from the water supply chamber.

4. In a jet condenser, the combination with one or more ejector condensing nozzles, of a water supply therefor, and an automatic means operated by the water supply flow velocity for controlling said supply to maintain a constant volume flow of water to the ejector nozzle or nozzles.

5. In a jet condenser, the combination with the condensing water chamber, of means adapted to cause the separation of air from the water delivered to said chamber, and means whereby a portion of said water in its condensing movement removes the air from said chamber.

6. A jet condenser having a condensing water chamber and a steam inlet chamber, a condensing nozzle connecting with the water chamber, means adapted to cause the separation of air from the water delivered to the water chamber, and a connection between the upper portion of the water chamber and the interior of said nozzle for removal of air from the water chamber.

7. A jet condenser having a condensing water chamber and a steam inlet chamber, a condensing nozzle connecting with the water chamber, means adapted to cause the separation of air from the water delivered to the water chamber, a connection between the upper portion of the water chamber and the interior of said nozzle for the removal of air from said chamber, and a float operated valve controlling said connection.

In testimony whereof, I have hereunto set my hand.

JOHN F. GRACE.
